GRANT E. SMITH, OF POUGHKEEPSIE, NEW YORK, ASSIGNOR TO POUVAILSMITH CORPORATION, OF POUGHKEEPSIE, NEW YORK, A CORPORATION OF NEW YORK.

STEERING-WHEEL POST.

1,213,811.

Specification of Letters Patent. Patented Jan. 23, 1917.

Application filed August 25, 1916. Serial No. 116,761.

To all whom it may concern:

Be it known that I, GRANT E. SMITH, a resident of the city of Poughkeepsie, in the county of Dutchess and State of New York, have invented an Improvement in Steering-Wheel Posts, of which the following is a specification.

This invention relates more particularly to steering wheel posts, that is to say, the casting which surrounds and in part supports the steering wheel shaft. Steering wheel posts have heretofore generally been cast from suitable metal and thereafter machined to size or drawn from metal to form a tubular post, and in practice considerable inconvenience has existed in assembling this post with its associated parts, either on account of the tubular post having sprung or become bent even slightly or on account of the difficulty of casting and machining, or drawing the same to exact size to fit the adjacent parts.

The principal object of this invention is to obviate these inconveniences and difficulties, by providing a steering post which, notwithstanding its tubular construction, will maintain itself in rigid and proper alignment at all times and particularly during shipping, and which may be molded or otherwise formed with such exact dimensions as to enable it readily to be assembled with its associated parts.

Another object of this invention is to combine with such a post the wire conductors for the several electrically operated mechanisms of a motor vehicle; the conductors being placed in circuit with a suitable switch or switches generally located on or near the steering post or wheel in order to be easily accessible to the operator, and further to insulate as well as to cover up and protect said wire conductors and to enable them to be connected into their respective circuits with the greatest ease and despatch when the car is assembled.

The accompanying drawings show one embodiment of the present invention, and there-in—

Figure 1 is a side elevation of an illustrative steering wheel post assembled; the steering wheel, parts of the steering-gear and the hood of a motor vehicle being shown partly in section and partly in elevation; Fig. 2 is a front elevation of the lower end of the post; Fig. 3 is a longitudinal section on line

3—3 of Fig. 1; and Figs. 4 and 5 are detail sections, the planes of the sections being respectively, the lines 4—4 and 5—5 in Fig. 3.

The principal object, aforesaid, of my invention may be accomplished by the use of a plastic material for the steering wheel post, such material being preferably condensite or bakelite or one of the condensation products of phenol and formaldehyde. These substances may be readily molded to exact size and thereafter hardened by suitable heat treatment. When so molded and hardened to form a tubular post, such materials produce a structure of great inherent rigidity admirably adapted to hold its shape, and in such a structure the advantages of a heavier cast and machined post are provided without excessive cost while the disadvantages of drawn metal tubular construction are entirely eliminated. Moreover, by embedding in the molded material the connecting wires, as presently described, a tubular post of added strength can be produced.

As shown in the drawings, plastic material *a* is preferably, though as at present believed not essentially, molded upon a wooden core *b*. This wooden core may be of material assistance in molding the plastic material and it will, to a certain extent, effect an economy in manufacture because less plastic material may be required when a wooden core is used. The condensite or like material permeates the wood of the core, thereby greatly strengthening the core and so unites itself to the wood during the molding process that a substantially integral steering post is formed. The wooden core may be tubular or solid when the molding is effected, and if solid it is subsequently bored to receive a steering shaft *c*, and to provide a slight clearance as indicated at *d*.

The requisite number of wires *d'* previously referred to may be embedded in the plastic material, preferably to lie longitudinally of the post, as shown. As a preferred method of embedding the wires in the plastic material of the post, they may be first laid upon or attached to the preferably wooden core *b* in the positions which they are to permanently occupy, before the plastic material is applied thereto. The subsequent covering of the core with the plastic material and the molding of the same thereon secures the wires permanently in position and not only covers and protects them but

may thoroughly and completely insulate them electrically. It may be entirely feasible in view of the insulating properties of the plastic material to embed bare wires in the post to form the several electrical circuits.

5 Suitable switches *e* to control the several electrical circuits may be mounted upon the steering wheel post in sufficient proximity to the wheel to be readily accessible to the operator, and suitable outlets for the circuits 19 may be provided by binding-posts *f* located preferably at the base of the column.

The switches herein shown are merely for purposes of illustration and the specific details of their construction and their operation in opening and closing the several circuits will be sufficiently understood and need not be herein described in detail. As shown, bases or mountings *g* for the switch boxes 15 are molded or formed integrally with the plastic material while contact points *h* are embedded therein and held firmly in place thereby. The appropriate connections may be made between the contact points *h* and the wires *d* preferably before the plastic 25 material is molded about the wooden core, and, as in the case of the wires *d*, the contact points *h* together with the binding-posts *f* may be attached to and held in position 30 by the wooden core during the molding and hardening of the plastic material. In the finished structure the contact points of the switches and the several binding-posts may be completely insulated by the plastic material molded around them. Metallic or other 35 caps *i* may be secured to the switch bases *g* and may carry appropriate switch control mechanism to coöperate with the contact points *h*.

40 When the post is assembled, the lower end may be supported as usual by a collar *j* secured to the casing for a steering gear, denoted generally by *k*, while its upper end may be supported by a bracket *l* bolted as 45 usual to the dash *m*, (see Figs. 1 and 2). As shown in the drawings, the steering wheel shaft *c* is connected to and supported at its lower end by the steering gear *k*, while the upper end is journaled in the steering 50 wheel post. To form a suitable bearing the plastic material of the post may extend inwardly beyond the wooden core at *n*; the shaft being thereby journaled directly upon and against the plastic material.

55 In assembling the completed steering wheel post into the motor vehicle the several electrical circuits may be completed by connecting the leading ends of the several conductors attached to the vehicle to the respective binding-posts upon the lower end 60 of the steering column.

An electrical circuit may also be provided for heating the steering wheel or for locating upon the steering wheel rim a suitable 65 switch button for closing a horn circuit and

the means for completing the circuit are herein provided as follows: the heating coil or horn button not being shown in the drawings. A ring *o* may be connected to a wire *p* leading to a corresponding binding post 70 located at the base of the column, in the same manner as the connecting wires *d*. The ring *o* may be embedded in the plastic material at the top of the steering wheel post and a brush *r* which is electrically connected to the heating coil or horn button by a wire *s*, may be so mounted that as the wheel turns it will always maintain its contact with the ring. The return circuit may be through the steering wheel shaft to 80 ground.

In the claims which follow the word "condensite" is used to refer generally to any plastic material capable of being molded to exact size and thereafter forming a rigid 85 hardened insulating material. It is to be understood that the invention may be variously embodied and modified within the scope of the subjoined claims.

I claim as my invention:

90 1. A steering wheel post for motor vehicles, comprising a hollow core adapted to contain the steering wheel shaft, and a covering of molded plastic material around the core and adapted to maintain the post in rigid alinement.

2. A steering wheel post for motor vehicles, comprising a hollow wooden core adapted to contain the steering wheel shaft, and a covering of condensite molded onto 100 the core and adapted to maintain the post in rigid alinement.

3. A steering wheel post for motor vehicles, comprising a hollow core adapted to contain the steering wheel shaft, and a covering of molded plastic material around the core and extending inwardly to form a bearing for said shaft.

4. A steering wheel post for motor vehicles, comprising a hollow core adapted to 110 contain the steering wheel shaft, and a covering of molded plastic material around the core, said plastic material extending beyond the core and inwardly at one end to form a bearing for said shaft.

115 5. A steering wheel post for motor vehicles, comprising a hollow core adapted to contain the steering wheel shaft, a covering of molded plastic material secured to the core, and a connecting wire for controlling any electrically operated part, 120 enclosed between said core and plastic material.

6. A steering wheel post for motor vehicles, comprising a hollow core adapted to 125 contain the steering wheel shaft, a covering of molded insulating material secured to the core, and a connecting wire for controlling any electrically operated part, 130 enclosed and held between said core and insu-

lating material and electrically insulated by said material.

7. A steering wheel post for motor vehicles, comprising a hollow core adapted to contain the steering wheel shaft, a covering of molded insulating material secured to the core, longitudinal wires embedded in said insulating material and held between the same and said core, connecting terminals for said wires embedded in said material, switches operatively connected with said wires, and a switch mounting formed integrally with said covering.

8. A steering wheel post for motor vehicles, comprising a single tube containing a hardened plastic material enabling the post to be molded to exact size and maintaining it rigidly against distortion, and means embedded in and insulated by said material to electrically connect two or more terminals.

9. The improvement in the art of assembling a plurality of electrical conductors which includes mounting said conductors upon a permanent core of insulating material, covering said conductors with a moldable plastic insulating material, and hardening said plastic material to retain said conductors permanently between said core and said plastic material.

10. The improvement in the art of assembling a plurality of electrical conductors which includes mounting said conductors and suitable terminals therefor upon a core of insulating material, surrounding said core with a moldable plastic insulating material thereby to cover said conductors and insulate said terminals, and hardening said plastic material to unite the same to the core.

11. The improvement in the art of making steering wheel posts for motor vehicles which includes mounting switch con-

tact points with connecting electrical conductors and conductor terminals upon a core of insulating material, surrounding said core with a moldable plastic insulating material, and hardening said plastic material thereby to completely insulate said conductors and to insulate said contact points and terminals from each other.

12. As an article of manufacture, a support for a plurality of electrical circuits comprising in combination, a hollow permanent core of insulating material, a plurality of electrical conductors attached to said core, and a covering of moldable plastic insulating material surrounding said core thereby completing the insulation of said conductors externally and from each other.

13. As an article of manufacture, a support for a plurality of electrical circuits comprising in combination, a hollow wooden core of insulating material, a plurality of electrical conductors attached to said core, and a covering of moldable plastic insulating material surrounding said core thereby completing the insulation of said conductors externally and from each other.

14. As an article of manufacture, a support for a plurality of electrical circuits comprising in combination, a core of insulating material, a plurality of electrical conductors attached to said core, a terminal for each said conductor likewise attached to said core, and a covering of moldable plastic material surrounding said core thereby completing the insulation of said conductors and insulating said terminals from each other.

In testimony whereof, I have signed my name to this specification this twenty-third day of August 1916.

GRANT E. SMITH.
